UNITED STATES PATENT OFFICE.

JOHN S. BAKER, OF LOS ANGELES, CALIFORNIA, ASSIGNOR TO ANDERSON-BARN-GROVER MANUFACTURING COMPANY, OF SAN JOSE, CALIFORNIA, A CORPORATION OF CALIFORNIA.

COOKING APPARATUS.

1,252,217.

Specification of Letters Patent.

Patented Jan. 1, 1918.

Application filed March 22, 1917. Serial No. 156,751.

To all whom it may concern:

Be it known that I, JOHN S. BAKER, a citizen of the United States, residing at Los Angeles, in the county of Los Angeles and 5 State of California, have invented certain new and useful Improvements in Cooking Apparatus; and I hereby declare that the following is a full, clear, and exact description thereof, reference being had to the accompanying drawings, which form part of 10 this specification.

This invention is a novel improvement in cooking machines of the type shown in my Patent #1,182,832 of May 9, 1916; such 15 machines, in general, comprising a tank adapted to be heated by hot water or steam, and a spiral canway in the tank along which the cans are moved by means of pusher bars connected with endless chains; the cans being fed into the canway by means of suitable devices at the feeding point, and discharged from the canway through an opening in one end of the tank and adjacent one of the bends of the canway.

20 As shown in my said patent the tank is provided with a large opening at the discharge end, said opening being closed by a series of removable gates, any of which gates may be detached to enable the cans to be 25 discharged through the opening left thereby.

The object of the present invention is to dispense with such a series of removable gates and enable the opening to be closed by a removable plate provided with a single 30 discharge port through which the cans are 35 discharged from the tank; the port being formed in the plate at such point therein that when such plate is fastened to the tank to close the large opening therein, the discharge port in the plate will come opposite 40 that run of the canway from which it is desired the cans shall be discharged.

By this invention the tanks may be made with one standard size large opening, and 45 the length of travel of the cans through the tank or cooking chamber is determined by the location of the port in the plate employed for closing said opening.

If desired a series of interchangeable 50 plates may be provided each adapted to close

the opening in the tank, the respective plates having the discharge ports therein located at different points in the lengths of the plates, so that by removing one plate and substituting another the point of discharge 55 of the cans from the canway can be changed, and the length or time of travel of cans in the cooking chamber determined.

This invention will enable a multiplicity of discharge gates, such as shown in my said 60 patent, in machines now in use to be dispensed with; and the tank to be made substantially steam-tight, and all the cans passed therethrough caused to travel a uniform form distance.

The word "can" as used herein is intended to cover all kinds of receptacles or packages that may be operatively handled in or treated by apparatus of the general character specified.

I will explain the invention with reference to the accompanying drawings in which:

Figure 1 is a partial end elevation of a cooker such as shown in my said patent, but provided with a novel plate for closing the 75 end opening therein.

Fig. 2 is an enlarged section on the line 2-2 Fig. 1 looking in the direction of the arrows.

Fig. 3 is an enlarged detail section on 80 the line 3-3 Fig. 1.

Fig. 4 is a front view of the closing plate in Fig. 1 detached.

Fig. 5 is a top plan view of said closing plate.

Fig. 6 is an enlarged left hand end view of such closing plate.

Fig. 7 is a view of another closing plate interchangeable with the plate shown in Figs. 4 to 6.

As indicated in the drawings the cooking machine preferably comprises a tank or cooking chamber 1 in which is arranged a flattened spiral canway 1^a, along which the cans are propelled by means of pusher bars 1^b attached to endless chains 1^c running over sprockets 1^d attached to shafts 1^e, which shafts are usually located at opposite ends of the tank and driven by suitable gearing exterior to the tank. The aforesaid parts 95 100

may be constructed in any suitable way, preferably substantially as described in my above mentioned patent, or in my Patent No. 1,181,057 of April 25, 1916.

5 The discharge end of the tank 1 is preferably formed by a casting 2 in which is a long transverse outlet opening, as described in my said Patent #1,182,832.

10 This opening is closable by a novel closing plate 5, which is provided with a bottom flange 5^a adapted to fit against the lower edge of the opening in the tank casting 2; (as indicated in Figs. 1 and 3) and is also provided with a top flange 5^b adapted to fit 15 against the upper edge of the opening in the casting 2, as shown in Figs. 1 and 3.

20 In the example shown the body of the closing plate 5 is not as long as the opening in casting 2; but the flange 5^b of the plate is 25 extended beyond the right hand end of the plate as shown at 5^c (Figs. 1, 4, 5,) the said flange and its extension equaling in length the opening in the casting 2. The space under the extension 5^c of the flange 5^b and between the right hand end of the plate 5 and the adjacent end wall of the opening in casting 2, forms a discharge port P, which comes directly opposite the last run of the canway 1^a, so that when the cans traversing the 30 canway reach port P they will be discharged from the tank through said port, as indicated in Fig. 2.

35 The lower edge of the closing plate 5 may be retained in position in the opening in casting 2 by means of lugs 6^a attached to angle plates 6 fastened to the casting 2 below the opening therein by means of bolts 6^b and nuts 6^c as indicated in Figs. 1 and 3.

40 The top flange 5^b of the plate is provided with notches 5^c to enable them to be slipped under or past locking pins 7 on the casting 2, and said pins 7 are provided with notches 7^a on their under sides, which notches are 45 adapted to be engaged by cam flanges 8^a on rods or handles 8, the inner ends of which are tapped into threaded sockets 5^e formed in the upper part and outer side of plate 5, (see Fig. 2). The outer ends of the rods 8 may be provided with knobs or handles 8^c 50 by which they can be readily manipulated.

55 The inner surface of plate 5 is concave and adapted to lie flush with the inner surface of the casting 2 and direct the cans around the bend of the canway 1^a, as indicated in Fig. 2. When the plate 5 is in place the cans can roll up on the inner surface of such plate (Fig. 3) in passing from the lower to the upper run of the canway, or vice versa.

60 It will be obvious that the port P could be formed at any desired point in the length of the closing plate 5 so that when such plate 5 was applied to casting 2 the port P would come opposite the desired run of the carrier. The closing plates 5 could be made 65 interchangeable with ports at different posi-

tions, and by removing one plate 5 and substituting another such as shown in Fig. 7 for example the point of discharge and the length or time and travel of the can through the canway and in the cooker could be controlled. 70

A set of such interchangeable closing plates might be provided for use with a single cooker, that closing plate being used whose port will suit the length or time of 75 travel which it is desired that the cans being treated shall have in the cooking chamber.

What I claim is:

1. The combination of a cooking chamber 80 having a large discharge opening; with interchangeable plates for closing the large opening, each plate having a single discharge port; the ports in the respective plates being differently located. 85

2. In combination a cooking chamber having a large discharge opening; with a detachable plate for closing said opening, said plate having a single discharge port, and said plate being interchangeable with another like plate having a differently located discharge port. 90

3. In combination a cooking chamber having a large discharge opening, a canway in the cooker; means for moving cans along 95 said way; a detachably attached plate adapted to close said opening to cause cans to pass it, said plate having a single discharge port so located as to come opposite a predetermined run of the canway to permit cans to 100 escape from the canway; said plate being interchangeable with like plates having differently located ports so that by substituting plates the point of discharge of the can can be varied. 105

4. In combination a cooking chamber having a casting at one end provided with a large opening; a single plate detachably attached to said casting to close the opening therein, said plate having a single discharge 110 port at the point at which it is desired to have the cans escape through the large opening, said plate being interchangeable with a like plate having a differently located port. 115

5. In combination a cooking chamber having a casting at one end provided with a large opening; a single plate detachably attached to said casting to close the opening therein, said plate having a single discharge port located therein at the point at which it 120 is desired to have the cans escape through the large opening; said plate being interchangeable with a like plate having a differently located port; with means on the casting for retaining the lower edge of the plate when 125 in position, and means attached to the upper edge of the plate and adapted to engage opposed members on the casting to secure the plate in position.

6. In combination a cooker having a large 130

discharge opening for the escape of cans at different points; and a removable plate for closing said opening having an extension on one end whereby when the plate is inserted in the opening a port is left for the escape of cans at one point only; with means on the cooker for retaining the lower edge of the plate when in position, and means attached to the upper edge of the plate and adapted to engage opposed members on the **10** cooker to secure the plate in position.

In testimony that I claim the foregoing as my own I affix my signature.

JOHN S. BAKER.
